226,771

PORTABLE EXERCISER

Lawrence I. Jacobs, P.O. Box 4092,
Palm Springs, Calif. 92262

Filed Sept. 13, 1971, Ser. No. 180,255

Term of patent 14 years

Int. Cl. D21—02

U.S. Cl. D34—5 K

FIG. 1 is a front perspective view of a portable exerciser showing my new design.

FIG. 2 is a right side elevational view thereof.

FIG. 3 is a top plan view thereof.

FIG. 4 is a bottom plan view thereof.

FIG. 5 is a rear elevational view thereof as taken from line 5—5 in FIG. 2.

I claim:

The ornamental design for a portable exerciser, substantially as shown.
